UNITED STATES PATENT OFFICE.

JOHN HALL THORPE, OF CHELSEA, LONDON, ENGLAND.

TOY PARACHUTE.

No. 910,157.

Specification of Letters Patent.

Patented Jan. 19, 1909.

Application filed December 16, 1907. Serial No. 406,730.

To all whom it may concern:

Be it known that I, JOHN HALL THORPE, a subject of the King of Great Britain, residing at Chelsea, in the county of London, England, have invented a new and useful improvement in Toy Parachutes, of which the following is a specification.

This invention relates to a toy of the parachute type and has for its object to provide an attractive article of this class which is capable of being thrown to a very considerable height before it opens and descends.

In order that my invention may be readily understood and carried into practical effect, reference is hereby made to the accompanying sheet of illustrative drawings wherein:—

Figure 1 is a view illustrating the device in its closed portion ready to be thrown into the air, while Fig. 2 illustrates a slightly modified form of the parachute in its open position.

In carrying my invention into practice, I provide a central stick or rod *a*, which is suitably weighted at one end, as at *b*. Associated with the said weighted stick *a* I provide a silk or other umbrella-shaped cover *c* of the usual kind used in connection with parachute toys, which cover, instead of being fixed to the stick as is usual, is connected loosely to said stick and arranged to be capable of sliding thereon, an opening of convenient size being provided in the said cover *c* through which the said stick *a* passes. The said cover *c* may be connected to the end of the stick *a* by means of the cords *c'* (see Fig. 2). Near the weighted end *b* of the central stick *a* I provide a circular frame

or ring *d*, which is connected, preferably, to the weight *b* by means of the radiating flexible members or cords *d'*, while connected to the parachute cover *c* and to the said circular frame or ring *d*, strings *e* are provided.

It will be understood from the foregoing that the construction and arrangement of the toy permit of the cover *c* being furled or rolled around the stick *a*, which is then grasped by the user's hand (see Fig. 1) and thrown, the said furling of the cover *c* in the manner shown enabling the device to be thrown to a considerable height but insuring its readily opening when it begins to descend.

Not only can the parachute be thrown to a considerable height, but the cords being arranged around the ring or frame *d* do not become entangled, while the ring or frame *d* also serves to distribute the weight of the stick over a greater area and as a consequence a steady descent of the parachute is insured.

What I claim as my invention, and desire to secure by Letters Patent, is:—

The new or improved toy parachute comprising the usual umbrella-like structure, a central stick weighted at its lower end, a horizontally-disposed ring or frame attached to said weighted stick by cords and to which the cords of the parachute are also attached, substantially as specified.

In testimony whereof I have signed my name to the foregoing specification in the presence of two subscribing witnesses.

JOHN HALL THORPE.
